DESIGN FOR PAPER-FILES.

Specification forming part of Design No. 7,246, dated March 17, 1874; application filed March 7, 1874.
[Term of Patent 7 years.]

B.

To all whom it may concern:

Be it known that I, OTTO F. FOGELSTRAND, of Kensington, in the county of Hartford and State of Connecticut, have invented and produced a new and original Design for a Paper-File, of which the following is a specification:

The nature of my design is fully represented in the accompanying cut, to which reference is made.

The base A has a rectangular projection at each corner, as shown. A flaring stand, B, surmounts the base A, which stand is octagonal at its base and square at the top. Four sides of this stand taper to a point at each

corner of the square top. The spindle C projects from the center at the top of the stand B. The surface of the parts A B is ornamented in any desired style.

I claim as my invention—

A design for a paper-file, in which the base has rectangular projections at each corner, and the stand is octagonal at its base and square at its top, substantially as described.

OTTO F. FOGELSTRAND.
